CLAIM

The ornamental design for a "monitor stand", substantially as shown and described.

DESCRIPTION

FIG. 1 is a top plan view of a monitor stand;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a back elevation view thereof;

FIG. 7 is a front, top, and right side perspective view thereof;

FIG. 8 is an enlarged view thereof, taken from FIG. 5; and,

FIG. 9 is an enlarged view thereof, taken from FIG. 6.

The features shown in broken lines form no part of the claimed design.

1 Claim, 9 Drawing Sheets
